UNITED STATES PATENT OFFICE.

IRVING G. DOWNS, OF HOLLIS, NEW YORK.

SLACK-ADJUSTER FOR RAILWAY-BRAKES.

1,186,385.

Specification of Letters Patent.

Patented June 6, 1916.

Application filed March 6, 1915. Serial No. 12,566.

To all whom it may concern:

Be it known that I, IRVING G. DOWNS, a citizen of the United States of America, residing in the village of Hollis, in the county 5 of Queens and State of New York, have invented certain new and useful Improvements in Slack-Adjusters for Railway-Brakes, of which the following is a specification.

10 My invention relates more particularly to automatic slack adjusters for railway brakes using shim plates, and the main object of my invention is to provide a more simple, convenient and efficient construction than here-15 tofore proposed for the purpose.

In the accompanying drawing, Figure 1 is a skeleton side elevation, illustrating one form of my invention in its application to the clasp type of brake; Fig. 2 is an enlarged 20 side elevation, partly in section, of the slack-adjusting end of the device; Fig. 3 is an enlarged plan on the line 3—3, Fig. 1, but drawn to a larger scale; Fig. 4 is a skeleton side elevation, showing the application of 25 the invention to a type of brake in which a single shoe is used for each wheel. Fig. 5 is a side elevation of a modification; Fig. 6 is a sectional plan on the line 6—6, Fig. 5, drawn to a larger scale.

30 Referring to Figs. 1, 2 and 3, showing the clasp-brake type, A A¹ are the wheels, and B, B¹ are the brake shoes, which are adapted to be pressed against the opposite sides of the wheels. At the left of Fig. 1 I have 35 shown in full lines the construction of parts according to my invention. On the right, for the other wheel, this construction is to be repeated, and for simplicity I have there indicated the parts 40 only diagrammatically. One of the brake shoes B for each wheel is shown pivotally connected to the live lever L, while the other shoe B¹ is pivotally connected to the dead lever D, swung at 20 from the frame F (indicated by dotted lines) and acted upon by 45 the release spring R. The brake shoe B is pivotally supported at 23 by a hanger and for this purpose I may make use of a lever H, which is pivoted at 21 to the frame F and whose principal function is hereinafter 50 described. The connections of the brake shoe B to the live lever L and to the lever H, may be by one and the same pivot pin or by another. The lower extended ends of the 55 live and dead levers L and D are connected with each other through a connecting rod in

the form of a pair of bars C, Figs. 1 and 3, the pivot pin p of the lever L being freely movable in longitudinal slots c in the bars C, as is common. Closely adjacent to the lower 60 end of this live lever L I mount the slack adjuster shim box or take-up device. In the preferred form the shim-containing box S is mounted on the inner ends of the bars C, while the bar T to coöperate with the shim 65 plates is shown as connected to the end of the live lever L, but this arrangement may be reversed, of course. I provide the lower end of the lever H, which I may term the slack-adjusting lever, with an extension h below 70 its pivotal connection with the shoe B, and this extension has a loose or free play connection with the adjusting bar G, as by making the connecting pin smaller in diameter than the hole or holes through which it 75 passes. This adjusting bar is slotted at 22 and is there connected through a friction clutch g to that part of the shim adjuster device which is secured to the bars C,—in this instance, the shim box S. This friction 80 clutch may be in the usual form of a bolt, nut and spiral spring, as indicated in Fig. 3.

In the described construction, the action 85 of the shim adjuster is as follows: As the shoes wear, the application of the brakes 90 will cause the adjusting bar G to be drawn farther to the left (Fig. 1), owing to the relative movements of the levers L and H, thus changing the point of connection of the adjusting bar G at g to the shim-box slack 95 adjuster. When the brakes are released again, the friction at g holds the bar G in its newly adjusted connection to the slack adjuster, with the effect of then allowing a shim plate to drop down behind the bar T. 95

In the construction described, it will be seen that by mounting the slack-adjuster near the bottom of the live lever, I am able to avoid the use of a long adjuster bar which in the clasp type of brake would have to extend across the face of the wheel and in the case of single shoe brakes would extend across or underneath the bolster. At the same time, I secure a very simple construction and action by the extension h on a 100 lever, such as the hanger lever H, connected to the frame and to the shoe to which latter the live lever is connected, so that relative movements of these two levers effect the slack adjustment automatically. In Fig. 4, 105 I have shown the same construction applied to a type of brake with but one shoe for each 110

wheel. In this case, A, A¹ are the two wheels, with brake shoes B and B¹, and L is the live lever, while D is the dead lever pivotally connected to the respective brake shoes.

5 The lower ends of these two levers are joined by a connecting rod C¹, the connection to the live lever being by a pin and slots, as before. This connecting rod carries the shim box S which has a pin and slot connection

10 through a friction clutch 9 to the short adjusting bar G. This latter has a loose or free play connection to the extension h of the lever H, which is pivoted to the frame at 21 and to the brake shoes at 23. The operation

15 of this construction is substantially the same as that described with reference to Figs. 1 to 3, as will be readily understood.

In the modification shown in Figs. 5 and 6 the adjusting bar G as a separate device

20 is dispensed with, and the lower end of the lever H is connected more directly to that part of the shim plate slack adjusting device which is not connected to the end of the live lever. As shown, the lever H is

25 connected to the slotted part of the connecting bar C¹ through the medium of a pin 24, which itself is held in the slot by a friction clutch device such as g¹. The end of the lever H has a loose or free-play connection with the pin 24, as by making the opening in the lever H for the passage of the pin larger than the diameter of the pin.

30 The shim box S is attached as before to the end of the bar C¹ while the other part of the adjuster is connected to the end of the live lever L.

I claim as my invention:

1. Railway brake means, comprising live and dead levers and connecting means and

40 brake shoes connected to said levers in combination with a shim-plate slack adjuster, and a slack adjusting lever bearing against the frame and pivotally connected to the brake shoe to which the live lever is connected, said slack-adjusting lever having an extension below the shoe connected to one part of the shim plate slack-adjuster while the live lever is connected to the other part of said adjuster, and friction means, inter-

45 posed between the slack adjuster and the slack adjusting lever for the purpose described.

2. Railway brake means, comprising live and dead levers and connecting means and

55 brake shoes connected to said levers in combination with a shim-plate slack-adjuster and a slack adjusting lever bearing against the frame and pivotally connected to the brake shoe to which the live lever is connected,

60 said slack adjusting lever having an exten-

sion below the shoe, with a pin and slot and friction connection to one part of the shim plate slack-adjuster while the live lever is connected to the other part of said adjuster.

3. Railway brake means, comprising live and dead levers and connecting means and brake shoes connected to said levers in combination with a shim-plate slack-adjuster near the lower end of the live lever, a slack

70 adjusting lever bearing against the frame and pivotally connected to the brake shoe to which the live lever is connected, said slack adjusting lever having an extension below the shoe, connected to one part of the shim plate slack-adjuster while the live lever is connected to the other part of said adjuster.

4. Railway brake means, comprising live and dead levers and connecting means, and

80 brake shoes connected to said levers in combination with a shim-plate slack-adjuster, and a hanger for the brake shoe to which the live lever is connected, said hanger having an extension below the shoe connected to

85 one part of the slack adjuster while the live lever is connected to the other, and friction means interposed between the slack adjuster and the slack-adjusting lever for the purpose described.

5. Railway brake means, comprising live and dead levers and connecting means, and

90 brake shoes connected to said levers in combination with a shim plate slack-adjuster and a hanger for the brake shoe to which the

95 live lever is connected, said hanger having an extension below the shoe, and an adjuster bar connected to said extension, and having a pin, slot and friction connection to one of the parts of slack adjuster, while the other part is connected to the live lever.

6. Railway brake means, comprising live and dead levers and connecting means and

100 brake shoes connected to said levers, in combination with a shim plate slack-adjuster closely adjacent to the end of the live lever, and a hanger for the brake shoe to which the live lever is connected, said hanger having an extension below the shoe connected to one part of the slack adjuster while the

110 live lever is connected to the other, and interposed friction means in connection with the hanger.

In testimony whereof I have signed my name to this specification, in the presence of

115 two subscribing witnesses.

IRVING G. DOWNS.
